UNITED STATES PATENT OFFICE.

CONRAD JACOBS, OF NEW YORK, N. Y.

SPARK-PLUG CLEANER.

Application filed December 20, 1921. Serial No. 523,705.

To all whom it may concern:

Be it known that I, CONRAD JACOBS, a citizen of the United States, and a resident of the city of New York, borough of the Bronx, 5 in the county of Bronx and State of New York, have invented new and useful Improvements in Spark-Plug Cleaners, of which the following is a full, clear, and exact description.

10 This invention relates to improvements in spark plug cleaners.

The general object of this invention is the provision of a durable and compact spark plug cleaner having a blade so shaped that 15 it serves for scraping and for fitting into the various grooves in a spark plug.

A further object of the invention is the provision of a spark plug cleaner having a blade which is of the thickness equal to 20 the proper distance between the terminals of a spark plug so that it may be used for spacing the terminals.

These objects are accomplished by providing 25 a spark plug cleaner constructed similar to a jackknife and having a blade, the end of which is squared and having the end portion extending at an angle to the plane of the blade.

These and other objects of the invention 30 will be more clearly understood from the following detailed description and accompanying drawings.

Figure 1 is a side plan view of the spark 35 plug cleaner;

Figure 2 is a top plan view of the spark plug cleaner with the blade rotated out of the handle casing; and

Figure 3 is a perspective view of the spark 40 plug cleaner with the blade enclosed.

Referring to the above-mentioned drawings, a two-edged blade 10 is shown with an approximately square end 11, the end portion 12 extending at an angle to the plane of the blade 10. The defining line between the 45 end portion 12 and the blade 10 extends diagonally across the blade so that the plane of the end portion 12 not only extends at an angle to the plane of the blade but also to a plane at right angles to the blade in passing through the median line of the same. The edges of the blade extend parallel to one another. The blade 10 is pivotally mounted in a casing 13 by means of the pin 50 14. A projection 15 integral with the blade

10 extends beyond the end of the casing 55 when the blade is enclosed therein. An offset 16 is provided in one wall of the casing 13 for protecting the end portion 12 which extends at an angle to the plane of the blade 10. The thickness of the blade 10 60 may be varied, but for use with the ordinary spark plug it would be made of a thickness nearly equal to the distance that the electrodes should normally be placed from one another. 65

In the use of this spark plug cleaner, the blade is rotated out of the casing by means of the projection 15. This blade has a squared end 11 which serves for scraping the walls of the spark plug by longitudinal movement of the blade. The end portion 12 is so curved that the blade may be projected into the spark plug and this end portion fitted into the grooves in the bottom of the chamber in the spark plug, the blade being provided with two edges 17 and 18 that may be used for scraping the wall by cutting in either direction. The thickness of the blade is such that it may be drawn between the electrodes of the spark plug, as shown in Figure 1, to remove the carbon that may have adhered, without altering the spacing of them. 75

I would state in conclusion that while the 80 illustrated example constitutes a practical embodiment of my invention I do not limit myself strictly to the exact details herein illustrated since manifestly the same can be considerably varied without departing from the spirit of the invention as defined in the 85 appended claims. 90

Claims:

1. A spark plug cleaner, comprising a handle, a blade pivotally mounted in the handle, said blade including a body portion, and an end portion lying in a plane extending at an angle to the plane of the body portion and intersecting it along a line extending diagonally of the axis of the body of the blade. 95

2. A spark plug cleaner, comprising a two-edged blade having an approximately square end, the end portion of said blade extending at an angle to the plane of the body of the blade, a casing in which the blade is pivotally mounted, said casing having an offset in one side for receiving the end portion of the blade, and a projection integral 100 105

with the blade and extending beyond the casing when the blade is enclosed therein for rotating the blade out of the casing.

3. As a new article of manufacture, a
5 spark plug cleaner of the class described comprising a two-edged blade having parallel cutting edges and an approximately

square end, the end portion of said blade extending at an angle to the plane of the blade, a casing handle in which the said 10 blade is pivoted, and means in conjunction with the blade for rotating it out of the casing.

CONRAD JACOBS.
